(57) **CLAIM**

The ornamental design for a basketball shooting training device, as shown and described.

DESCRIPTION

FIG. 1 is a top perspective view of a basketball shooting training device, showing the new design;

FIG. 2 is a top view;

FIG. 3 is a bottom view;

FIG. 4 is a side elevation view;

FIG. 5 is a side elevation view of the side opposite of that shown in FIG. 4;

FIG. 6 is a rear view; and,

FIG. 7 is a front view.

The broken lines of FIGS. 1-7 are for illustrative purposes only and form no part of the claimed design.
